UNITED STATES PATENT OFFICE.

JOHN ECKERT, OF MILWAUKEE, WISCONSIN.

GEAR-WHEEL FORGING DIES AND METHOD OF MAKING SAME.

Application filed May 24, 1920. Serial No. 383,850.

To all whom it may concern:

Be it known that I, JOHN ECKERT, a citizen of the United States, residing at Milwaukee, county of Milwaukee, and State of Wisconsin, have invented new and useful Improvements in Gear-Wheel Forging Dies and Methods of Making Same, of which the following is a specification.

My invention relates to improvements in gear wheel forging dies and methods of making the same.

The object of my invention is to expedite, improve and cheapen the method of manufacturing gear wheels and particularly to provide an inexpensive method of manufacturing forging dies having pattern teeth cut therein whereby pieces of heated metal may be hammered into conformity with the pattern dies and the dies frequently replaced at small expense when they become worn or distorted under the severe impacts to which they must be subjected in order to force the metal into perfect conformity with the pattern. My improved dies may be used both as forging hammers and as anvils, in fact I use them in both relations in a single forging operation wherein the forging hammer embodying my improvement is first reciprocated into and out of contact with a block of heated metal to forge it into a circular blank having teeth thereon conforming generally to the contour of the desired gear wheel and its teeth, after which the blank is placed in an inverted position upon an anvil die embodying my invention and a forging hammer reciprocated into contact with its upper surface until the teeth have been pressed into absolute or substantially absolute conformity with the pattern provided by the anvil die.

The object of my invention includes the provision of means whereby the gear tooth forming portion of the die may be readily cut along radial lines to form grooves, the walls of which conform perfectly to the contour of the teeth to be forged in an ordinary gear tooth cutting machine or lathe, this portion of the die being separately formed and subsequently assembled with the central portion and in an outer portion concentric with the central and tooth carrying portions.

My invention is peculiarly adapted to facilitate the manufacture of beveled gear wheels altho my method may be followed and my improved die used also in the manufacture of crown wheels or any gear wheel in which the teeth project laterally from one

side thereof. Beveled gear wheels can be produced at a rate of many hundreds or even thousands in a single day as the output from a single set of forging dies consisting of a 60 contouring forge, a punch and a finishing forge.

In a companion application bearing even date herewith, Serial Number 383,849, filed May 24, 1920, I have shown and described 65 an improvement in gear wheels and methods of manufacturing the same, in the practice of which method I employ the improved dies herein disclosed and illustrated in the accompanying drawings with reference to 70 which my method is herein described.

In the drawings:

Fig. 1 is a vertical sectional view of the hammer and anvil die of a gear wheel finishing forge with the gear wheel in position 75 and the hammer in contact therewith, the anvil die being constructed in accordance with my invention.

Fig. 2 is a fragmentary view of a cylindrical blank from which the grooved portion 80 of my improved die is to be formed.

Fig. 3 is a side view of the grooved portion of the anvil die separated from its concentric central and outer portions.

Fig. 4 is a fragmentary sectional view 85 showing the tooth forming portion of my improved die in assembled relation to the central block or core piece as it appears preparatory to applying the outer cylinder.

The method of manufacturing my improved dies consists in first forming a cylindrical blank 1 having at one end a thickened portion 2 as shown in Fig. 2, both the inner and the outer surfaces of the blank being conically enlarged to form this thickened portion. The portion 2 conforms generally in its internal and external diameters of the toothed portion of the beveled gear wheel to be formed. This blank illustrated in Fig. 2 is then placed in a lathe or gear cutting machine and radial grooves 3 cut therein as shown in Fig. 3. The walls of these grooves conform to the surfaces of the gear teeth to be formed. They extend entirely across the thickened portion 2 from the outer to the inner side and they may therefore be readily cut in a lathe or gear cutting machine. The portions 4 between the grooves are finished in conformity to the contour of the spaces between the gear teeth 100 of the gear wheel to be produced. The inclination or degree of bevel is of course de-

terminated by cutting or shaping the end 2 of the cylinder, preferably before cutting the channels therein.

After cutting the portion 2 of the blank 5 and conforming its surfaces to serve as a pattern die for the toothed portion of a beveled gear wheel to be produced in the forge, the cylinder is then heated and applied to a central cylindrical block or holder 10 5 as shown in Fig. 4. The outer surface of this block conforms to the inner surface of the blank shown in Fig. 2, whereby, when the cylinder cools, it will shrink upon the block 5. It is obvious that by making the 15 central block 5 of sufficient diameter so that the cylinder when heated can be closely fitted thereto, the shrinkage of the cylinder as it cools will cause it to grip the block with great force, producing substantially an 20 integral structure. Thereupon an outer ring or cylinder 7 may be formed and shrunk upon the outer surface of the cylinder 1 in a similar manner. This outer cylinder 7 is shaped at one end to conform 25 to the outer surface of the enlarged portion 2 of the cylinder 1 and both the central cylinder 5 and the outer cylinder 7 are so formed as to close up the ends of the grooves 3, whereby the heated block or blank of 30 metal from which a gear wheel is to be formed may be hammered into these grooves and conformed thereto to produce the desired gear teeth on the blank.

As set forth in said companion application, a die embodying the invention herein described may be first employed as a forging hammer to upset gear teeth on a block of heated metal while supported upon an anvil having a circular recess, to the contour of which the block of heated metal will be conformed during the hammering and tooth upsetting process. Thereafter the heated block or blank may be inverted and placed upon an anvil die also constructed 40 in accordance with and embodying the invention herein disclosed and the upper surface of the blank hammered until the teeth are brought into substantially perfect conformity to the walls of the grooves 3 in the die. Whenever a die becomes distorted or 45 injured by the forging operation, it may be immediately discarded and another die substituted at small expense for the reason that my improved process enables me to form 50 the grooves 3 in a lathe and subsequently close up the ends of the grooves with the inner and outer members 5 and 7, thus avoiding the great expense which would be involved in drilling, cutting and contouring 55 the grooves in a single solid block of metal having the form of the die shown in Fig. 1.

I claim:

1. The method of making gear wheel 60 forging dies consisting in cutting the end 65 of a cylindrical blank along radial lines to

form grooves and intervening projections adapted to serve as a pattern for the toothed portion of a gear wheel having laterally projecting teeth, heating said cylinder and shrinking the same upon a central cylindrical block conformed to the inner surface of the blank and adapted to close up the inner ends of said grooves, and subsequently shrinking a larger cylinder upon the outer surface of the grooved cylinder in a position to close up the outer ends of the grooves. 70 75

2. The method of forming gear wheel forging dies, which consists in forming a cylindrical blank, with inner and outer walls conically enlarged at one end and conformed in the inclination of its outer surface to the inclination or bevel of the toothed portion of a beveled gear wheel cutting radial grooves in said contoured portion and conforming the surfaces of the grooves and the intervening portions to serve as a pattern for the toothed portion of the gear wheel, and subsequently closing the ends of the grooves with a central core 80 85 and enclosing cylinder. 90

3. The method of forming gear wheel forging dies, which consists in first forming a tooth shaping portion having channels conforming in contour to the gear teeth to be forged therein, and then uniting it with other members of the die to provide rigid closures for the ends of the channels, whereby a heated gear wheel blank may be applied to the die and forged on the blank 95 100 into exact conformity with the contour of the die channels.

4. The method of forming gear wheel forging dies, which consists in first forming a tooth shaping portion having tooth-shaped channels, and then uniting it with other members of the die to rigidly close the ends of such channels. 105

5. A gear wheel forging die, including the combination of a set of rigidly connected concentric members including a central core an intermediate work forming member shrunk upon the core, and an outer work forming member shrunk upon the intermediate member. 110 115

6. In a gear wheel forging die, the combination with a cylindrical member having a conical end provided with teeth, of a core for said cylindrical member, and a second cylindrical member disposed about the first mentioned member, said core and second cylinder member being adapted to close the ends of said teeth. 120

In testimony whereof I affix my signature in the presence of two witnesses.

JOHN ECKERT.
